UNITED STATES PATENT OFFICE

FREDERICK A. BALLOU, OF NAYATT, RHODE ISLAND, ASSIGNOR TO B. A. BALLOU & CO. INC., OF PROVIDENCE, RHODE ISLAND, A CORPORATION OF RHODE ISLAND

SHOE STRAP

Application filed February 6, 1928. Serial No. 252,214.

This invention relates to an improved construction of extendible shoe strap; and has for its object to provide a shoe strap of this character of a length to extend over the in-
5 step of the wearer and is provided at its ends with attaching means for securing the strap ends to the margins of the shoe upper.

A further object of the invention is to provide an extendible shoe strap of this character having an extendible core connected to the attaching end members and having a flexible sleeve covering the core.

The invention further consists in the provision of a cuff member attached to each of 15 the clips or attaching end members into which the ends of the sleeve or covering slidably extend.

With these and other objects in view, the invention consists of certain novel features 20 of construction, as will be more fully described, and particularly pointed out in the appended claims.

In the accompanying drawings:

Figure 1 is a perspective view of a shoe 25 showing my improved strap attached thereto.

Figure 2 is a top view of one of the end attaching members hingedly connected to the cuff member.

Figure 3 shows the under side of the cuff 30 attaching member shown in Figure 2.

Figure 4 is a central side elevation of the members illustrated in Figures 2 and 3.

Figure 5 is a top view of the strap in ex- 35 tended position.

Figure 6 shows one construction of my strap in section.

Figure 7 is an enlarged view showing an 40 end portion of the strap illustrating a chain for limiting the extending motion of the strap and showing the sleeve as withdrawn from the outer edge of the cuff member.

Figure 8 illustrates the strap in contracted 45 position with the strap limiting chain slack and the end sleeve extending into the cuff member.

Figure 9 is a section on line 9—9 of Figure 5.

Figure 10 is a perspective view showing an 50 other form of core which is constructed of

expandible wire fabric through which extends a pair of springs.

Figure 11 illustrates a strap of my improved character with an ornamental member centrally mounted thereon.

It is found in the practical use of extendible shoe straps of this character of advantage to provide such a strap having attaching members at its ends to be clamped or otherwise attached to the marginal edges of a shoe and to have a flexible extendible core connected to these attaching end members, the core being covered with a flexible sleeve preferably of non-metallic material such as leather, or fabric and in some instances to provide a cuff member connected to each of the attaching clamps or members into which the ends of the sleeve extend to slide on the sleeve as the strap is extended or contracted; and the following is a detailed description of the 60 present embodiment of my invention and showing one construction of strap by which these advantageous results may be accomplished:

With reference to the drawings, 10 designates one form of attaching member or clip, each being provided with a top plate 11 and a clamping finger 12, the latter preferably having a tooth 13 to engage the inner surface of the shoe margins and the inner end of this 65 top plate is rolled to provide an eye 14 through which a pivot pin 15 is passed to connect this clamping member to the metal cuff member 16.

A core member 17 may be provided of any 70 suitable flexible extendible material such for instance as a coil spring wound into the desired form in cross section, the opposite ends of the spring being connected as at 18 to the pins 19 in the opposite cuffs 16. Over this 75 core member I loosely draw a sleeve 20 of suitable flexible material preferably non-metallic material, such for instance as leather, fabric, celluloid or other suitable material which need not be necessarily extendible.

This sleeve may be connected at its middle portion by a pin 21 extending through it and the core if desired or any suitable means may be employed for connecting this sleeve to the core. The opposite ends of this sleeve 80

may be extended into their respective cuff members 16 to slide therein as the strap is extended and contracted. This sleeve and its cuffs may be suitably ornamented to serve as a handsome finish to the strap.

5 In some instances, instead of forming the core 17 by winding a spring wire into a coil of the desired shape in cross section I may employ other constructions such as a metal fabric 22 through which a pair of coil springs 23 may extend to be connected to the opposite sleeve pins 19 and over this I may draw the covering sleeve 20 of leather or other desired flexible material.

10 13 In some instances, I may extend a chain 25 or other suitable member through the core to limit the amount of its extension while in other instances the metal fabric 22 may serve this purpose.

15 20 In some instances I may desire to mount or attach an ornament 24 to the strap as best illustrated in Figure 11.

25 23 My improved extendible shoe strap when covered with a leather sleeve may conform in shade or color to the rest of the shoe or it may be ornamented in any suitable way to suit the taste of the individual wearer.

30 33 The foregoing description is directed solely towards the construction illustrated, but I desire it to be understood that I reserve the privilege of resorting to all the mechanical changes to which the device is susceptible, the invention being defined and limited only by the terms of the appended claims.

35 I claim:

1. An extendible shoe strap having an attaching member at each of its ends, an extendible core connected to said attaching members, and a flexible tubular sleeve secured to and covering said core substantially from one clip to the other.

40 45 50 An extendible shoe strap having an attaching member at each of its ends, and a flexible extendible core connected to said attaching end members and a flexible non-metallic tubular sleeve secured to and over said core and forming the uninterrupted complete outer surface of said strap.

55 50 An extendible shoe strap having an attaching member at each end thereof, a flexible extendible core connected to said end members, and a leather sleeve over said core and in telescopic engagement with said end members.

60 55 65 An extendible shoe strap having an attaching member at each end thereof, a continuous flexible extendible metallic core connected to said end members, and a continuous flexible non-metallic sleeve covering said core and in telescopic engagement with said end members.

65 65 70 An extendible shoe strap having an attaching member at each end thereof, a flexible extendible core connected to said end members, a flexible non-metallic sleeve over

said core, and a cuff connected to each attaching member slidingly engaging the end portions of the sleeve.

70 75 80 An extendible shoe strap having an attaching member at each end thereof, a flexible extendible core connected to said end members, means for limiting the extension of the core, a sleeve of non-metallic material loosely mounted on said core, and cuff members connected to said attaching members into which the ends of the sleeve slidably extend.

85 In testimony whereof I affix my signature.

FREDERICK A. BALLOU.
